UNITED STATES PATENT OFFICE.

IRA F. PECK, OF CRANSTON, RHODE ISLAND.

MACHINE FOR SETTING LACING-HOOKS.

SPECIFICATION forming part of Letters Patent No. 774,271, dated November 8, 1904.

Application filed September 25, 1903. Serial No. 174,671. (No model.)

To all whom it may concern:

Be it known that I, IRA F. PECK, a citizen of the United States, residing at Cranston, in the county of Providence and State of Rhode Island, have invented certain new and useful Improvements in Machines for Setting Lacing-Hooks, of which the following is a specification, reference being had therein to the accompanying drawings.

10 My invention relates to machines for setting lacing-hooks wherein a plunger reciprocates in conjunction with a stationary upper anvil to set the eyelet portion of the hook, and has for its object the ends commonly sought in such machines.

This invention resides primarily in the novel structure and combination of the setting-tools and their actuating mechanism.

In the drawings forming part of this specification, Figure 1 is a side elevation, partly in vertical section, of a machine embodying my invention; Fig. 2, a similar view of the driving-shaft and one of the cams, showing one cam-channel in dotted lines; Fig. 3, a central vertical section of the reciprocating plunger and adjacent parts; Fig. 4, a transverse section of the same on line xx of Fig. 3; Fig. 5, a side elevation of the entire machine; and Fig. 6, a transverse section of the mechanism, taken on line yy of Fig. 1.

Like reference-numerals indicate like parts throughout the views.

The frame or body 1 of my machine is provided with a yoke 2, carrying an anvil 3, vertically adjustable by milled nuts 4 upon its upper portion. The usual downwardly-inclined run 5 guides the hooks to the throat portion 54, which leads to the setting mechanism. Transversely mounted in the machine-frame is the shaft 6, driven by the pulley 7 and carrying the disks 8 and 10. The shaft 6 passes through a slot 11 in a reciprocating bar 12, and this bar 12 has pivoted to its forward extremity toggle-links 14 and 13, whose opposite ends are respectively connected to the plunger 16 and to the pin 15, vertically adjustable in the frame by nuts 55^x on a threaded sleeve 56^x. An adjusting-screw 17, mounted in the frame, supports the

lower edge of the bar 12. This bar is reciprocated by a roller 38, traversing the channel 39 of the disk 10.

A sliding dropper 9, with detent 19 for separating the front hook from a series upon the run, is attached to the extremity of a link 20, whose opposite end is connected with one arm of the bell-crank lever 21, mounted upon guide-block 55 on the frame. The other lever-arm, 22, is provided with a slot which engages a pin 23, projecting from the inner face of a slide 24, mounted in the guide-block 55, depending from the frame. The rear end of the slide is provided with a roller 25, which registers with the channel 26 in the outer face of disk 8.

For conveying the separated hook to the setting-tools is a pusher 27, pivoted at its lower extremity to a projection 28 upon the frame adjacent the plunger. Attached to the pusher 27, above its pivoted extremity, is a link 29, connected with a bar 30, whose opposite end is retained by a pin 31 and cushioned by a spring 32 in the elevated arm 33. The latter is provided with a slot 34 to admit a pin 35, fixed to the machine-frame, and is longitudinally reciprocated by roller 36, which travels in a channel 37 in the disk 8.

65 Reciprocating circular motion is imparted to the setting die-head by means of the following mechanism: A lever 40 is pivoted to the machine-body with its lower end engaging a pin 41 projecting from the slide 24 through the slot 42 in the guide-block. The upper end of lever 40 is connected by a link 43 to a rack 44, mounted to slide in the machine-frame adjacent the plunger. The rack engages a pinion 45, which meshes with a segmentally-toothed sleeve 46, rotatably mounted in the machine-frame and through which the plunger 16 reciprocates vertically as a 70 sliding fit. In this plunger is a vertical stem 49, provided with a setting die-head 47, normally resting upon the top of plunger. A portion of the die-head is cut out, as at 48, to allow removal of the lacing-hook after the 75 setting operation. Below the head is vertically mounted in a pocket 16^x within the plunger a spring-pin 53 with a concave top and

adapted to hold the hook in frictional contact with the under side of the die-head 47 during the swaging operation. A pin 50 projects from the stem, 49, traversing the plunger 16 through a radial slot 52 and engaging a vertical keyway 51 in the inner face of sleeve 46. Thus any rotary motion of the sleeve is imparted to the die-head 47 without imparting such motion to the plunger 16. A stop-pin 56 in the plunger 16 prevents excessive upper travel of the pin 53.

The operation of my machine is as follows: A hook slides from the run 5 into dropper 9. The revolution of the disk 8 upon the driving-shaft 6 lowers the dropper 9, and the hook enters the throat portion 54 of the run, where it is thrust forward by the pusher 27, actuated by the disk 8, into position intermediate the head 47 and spring-pin 53. Meanwhile the rack 44 has advanced and rotated the die-head 47 into the position shown in broken lines in Fig. 6. Thereupon the reciprocating bar 12 is thrown forward, and the plunger 16, with the hook engaged thereon to the die-head 47, is caused to vertically rise through the sleeve or sector member 46 to its fullest height and the lacing-hook set in contact with the anvil 3. The plunger then recedes a certain distance far enough from the point of the setting-die to clear the hook, then makes a partial revolution in order to bring the opening in the die-head or top plate 47 opposite the opening or pocket 16^x in the plunger 16 to allow the hook to be expelled. After the partial turn of the die, as above described, which brought the opening of the die-head and the die in alinement, the plunger continues its downward travel, and at the end of said travel the top plate has been turned back into position to receive another hook or the position indicated in Fig. 6 of the drawings. This movement of the die-head in relation to the die and their respective segmental openings is important, since the registration of the latter facilitates the discharge of the hook that has been previously worked upon and is a distinct advantage, as will be readily seen. It will also be noted that the setting die or plate at the instant of the setting operation has a decidedly firm bearing upon the top of the supporting die or plunger, giving stability and permanency to the structure, which is most desirable.

Having described my invention, what I claim is—

1. In a machine of the class described, the combination with a plunger, of a revoluble die mounted in the plunger, a rotatable sleeve surrounding the plunger and connected with the die, and means exterior the plunger for rotating the sleeve.

2. In a machine of the class described, the combination with a plunger, of a revoluble die mounted in the plunger, a rotatable sleeve

surrounding the plunger and connected with the die, and means exterior the plunger for imparting reciprocating circular motion to the sleeve.

3. In a machine of the class described, the combination with a plunger of a revoluble die mounted in the plunger, a sleeve embracing the plunger, a pin in the die engaging the sleeve, and means engaging the sleeve for rotating the latter.

4. In a machine of the class described, the combination with a plunger of a revoluble die mounted in the plunger, a sleeve embracing the plunger, a pin in the die loosely traversing the plunger and contacting with the sleeve, and suitable mechanism for rotating the sleeve.

5. In a machine of the class described, the combination with a plunger of a revoluble die mounted in the plunger, a sleeve embracing the plunger, a member loosely traversing the plunger, and connecting the die and sleeve, and suitable mechanism engaging the sleeve for circularly reciprocating the sleeve.

6. In a machine of the class described, the combination with a plunger of a revoluble die mounted in the plunger, a segmentally-toothed sleeve embracing the plunger, a pin in the die loosely traversing the plunger and engaging the sleeve, a pinion, engaging the toothed sleeve, and means for actuating the pinion.

7. In a machine of the class described, the combination with a plunger of a die mounted in the plunger, a toothed sleeve embracing the plunger, means independent of the plunger connecting the die and sleeve, a pinion engaging the sleeve, a rack-bar engaging the pinion, and means for reciprocating the rack-bar.

8. In a machine of the class described, the combination with a plunger of a die rotatably mounted in the plunger, a head upon the die provided with a segmental opening, and a spring-pin vertically mounted in the plunger beneath the head.

9. In a machine of the class described, the combination with a plunger of a die rotatably mounted in the plunger, a head upon the die, and a spring-pin with a concave top mounted in the plunger and adapted to approach the under surface of the head.

10. In a machine of the class described, the combination with the frame, of a run upon the frame, a sliding dropper having a detent at its free end and intersecting the run, a connecting-link to which the dropper is pivoted, a bell-crank lever mounted on the frame and pivoted to the connecting-link, and means for reciprocating the free arm of the bell-crank lever.

11. In a machine of the class described, the combination with the frame of a run upon the frame, a sliding dropper having a detent at its free end and contiguous to the run, a connecting-link to which the dropper is pivoted,

a bell-crank lever mounted upon the frame and pivoted to the connecting-link, a slide mounted in the frame, a pin in the slide engaging the free arm of the bell-crank lever, 5 and means for reciprocating the slide.

12. In a machine of the class described, a sleeve, a plunger vertically movable in said sleeve, said plunger having a pocket at its upper end, a die mounted in said plunger, a die-head having an opening, and means for causing the plunger to move vertically to its fullest extent and means to then cause the die to make a partial revolution to bring said opening and pocket coincident. 10

13. In a machine of the class described, the combination of a plunger, a die mounted in the plunger, a rotatable sleeve through which the plunger is vertically movable, means for moving the plunger vertically to its fullest 15

extent, then to recede the plunger a part of 20 its travel and means to then cause the die to make a partial revolution as and for the purpose specified.

14. In a machine of the class described, the combination of a plunger, a revoluble die 25 mounted therein, a sleeve surrounding the plunger and connected with the die, means for revolving the sleeve, and a die-head, the construction being such that the setting-die is afforded a firm bearing on the top of the 30 supporting die or plunger at the time of the setting operation, as set forth.

In testimony whereof I have affixed my signature in presence of two witnesses.
